SEWING-MACHINE.

1,202,204.

Specification of Letters Patent.

Patented Oct. 24, 1916.

Application filed July 23, 1912. Serial No. 711,022.

To all whom it may concern:

Be it known that we, GEORGE E. MOLYNEUX and GEORGE S. GATCHELL, citizens of the United States, residing, respectively, at 5 Bayonne, in the county of Hudson and State of New Jersey, and Roselle Park, in the county of Union and State of New Jersey, have invented certain new and useful Improvements in Sewing-Machines, of which 10 the following is a specification, reference being had therein to the accompanying drawings.

This invention relates to improvements in sewing machines employed in the manufacture of garments made from knit fabrics, and is especially designed for overseaming a previously formed seam, as when attaching a sleeve to the body portion of a garment, in which operation the sleeve is first attached 20 by a seam placed close to the free edges of the fabric, leaving such edges exposed and effecting an undesirable ridge which is later covered by overseam stitches which act to cover and flatten the seam.

25 The object of the invention is to provide means for insuring that the covering seam will substantially correspond in length to the first placed seam or, if used singly, to substantially the length of the free edges of 30 the fabrics before being joined.

It is well understood that when stitching together limp elastic materials under ordinary sewing conditions, the action of that portion of the feed-dog located back of the 35 line of needle actuation tends to stretch the free edges of the materials, due to the resistance offered by the action of the receiving end of the cloth-presser on the materials in advance of the line of needle actuation, and 40 to overcome this difficulty there is herein provided a work-retarding member located at the rear of the needle and coacting with the cloth-presser to slightly retard the material in opposition to the feed movements of 45 the feed-dog, thus preventing the latter from stretching the material between the receiving and delivery ends of the cloth-presser.

Heretofore it has been common to provide feeding mechanisms with a plurality of feed-dogs having feed movements of different amplitude for overseaming a previously formed elastic seam, but such earlier constructions have proved objectionable because

of their inability to meet the requirements of turning corners, owing to one of said feed-dogs in its movements not passing the line of needle actuation in the direction of the feed, and their inadaptability for use in connection with cylinder bed machines, wherein the tubular work-supporting member is required to be constructed of very small diameter to accommodate the smallest size tubular work, such as the sleaving of infants' garments, and also because of the increased complication of the feeding mechanism which, of necessity, has to be constructed and arranged to accommodate the requirements of the stitch-forming mechanism.

The present invention is preferably embodied in a cylinder bed machine having feeding mechanism including a feed-dog for advancing the work lengthwise of the work-supporting bed, the work-retarding member being mounted independent of the feeding mechanism and adapted to be projected 70 within the line of action of the feed-dog above the surface of the cylinder bed and connected with means located below said bed and under the control of the operator whereby the work-retarding member may be controlled at will.

The invention is represented in the accompanying drawings embodied in a cylinder-bed feed-up-the-arm machine of the type shown and described in our pending application Serial No. 521,801, filed October 9, 1909, Figure 1 being a sectional rear side elevation and Fig. 2 a sectional plan of the same. Fig. 3 is a perspective view representing a part of the feeding mechanism and the work-retarding device. Fig. 4 is a perspective view showing the work advancing and retarding elements in conjunction with a presser-foot, and with an interposed section of fabric.

The frame of the machine is shown formed with the hollow base 1 and standard 2, laterally extending tubular arm 3 culminating in the head 4, and cylinder-bed or work-supporting horn 5 having at its rearward end the flange 6 secured to the base beneath the over-hanging arm 3. Journalized in suitable bearings in the base and the horn 5 is the main-shaft 7 carrying the grooved belt-wheel 8 and formed with the crank 9 connected by means of the pitman 10 with the

crank-arm 11 fixed upon the rearward end of the needle-actuating rock-shaft 12 which is provided at its forward end with the crank-arm 13 connected by means of the link 14 with a collar 15 fixed upon the needle-bar 16 carrying needles 17.

Coöperating with the needles is a looper 18 secured upon the rocking carrier 19 which is pivotally mounted upon the forward end of the looper-supporting rock-shaft 20 journaled within and lengthwise of the cylinder-bed 5 and having an operative connection, including the pitman 21 and crank-arm 22, with the needle-actuating shaft 12 from which the looper derives its operative loop-seizing movements. The carrier 19 derives its rocking movements from a connection with the endwise jogging bar 23 which is connected in turn with a crank-disk 24 upon the reduced forward portion 7' of the main-shaft 7.

The work-advancing mechanism comprises a feed-dog 25 formed with several spaced serrated feeding surfaces and having its shank 26 secured by means of the fastening screw 27 upon the channeled forward portion 28 of the feed-bar 29 which is shown formed with a contracted portion 30 slidably fitted within bearing bosses 31 of a fulcrum-block provided with the transverse bosses 32 embraced by and pivotally mounted by means of the screw-pins 33 upon the spaced arms 34 of a bifurcated post or lifting bar having a boss 35 fitted upon the feed-lifting eccentric 36 fixed upon the main-shaft section 7'.

Mounted upon and rotating with the main-shaft is the feed-actuating eccentric 37 which is embraced by the strap 38 at one end of a pitman-rod 39 having at its opposite end a strap 40 embracing a stud 41 upon one arm 42 of a rocking sleeve 43 mounted upon the fulcrum-stud 44 and having a second arm 45 carrying a stud 46 which is embraced by the strap 47 at the rearward extremity of the feed-bar 29. Through the connections just described the feed-bar, and hence the feed-dog, derives reciprocatory movements lengthwise of the cylinder-bed 50 for the propulsion of the work, while the rising and falling movements are communicated to the feed-dog through the vertical movements of the fulcrum-block 31 derived from the eccentric 36.

Journaled in the head 4 of the bracket-arm is the usual spring-pressed presser-bar 48 having secured thereto by means of the screw 49 the presser-foot shank 50 which is shown carrying in its reduced lower extremity the longitudinal fulcrum-pin 51 sustaining the tilting block 52 formed with spaced longitudinally extending ears 53 to which are pivotally connected by studs 54 the ears 55 extending upwardly from the pressure-plate 56 which is shown provided with the

depending rib or keel 57 and with needle-apertures 58. By its described universal pivotal connection with the shank 50, the pressure-plate 56 is capable of tilting crosswise and lengthwise of the direction of feed 70 so as to accommodate itself effectively to the work.

Secured upon the forward end portion of the cylinder-bed 5 by means of fastening screws 59 is the throat-plate 60 having the 75 needle-apertures 61 and the parallel feed-dog apertures 62 the outer ones of which are elongated to receive the upwardly extending work-retarding lugs 63 upon the spaced arms 64 connected at their rearward ends by 80 the cross-plate 65 together constituting a lateral member of an angle-lever formed with a depending arm 66 and fulcrumed at the junction of its arms by means of the stud screw 67 upon lugs 68 projecting forwardly 85 from the arched sustaining bar 69 which is rigidly secured at opposite ends by means of screws 70 in the upper portion of the arm 5 adjacent the fulcrum-block 31 above the feed-bar section 30.

To the depending angle-lever arm 66 is connected by means of the screw-pin 71 the forward end of a link 72 extending rearwardly through the arm 5 and pivotally attached at its rearward end by means of the 95 screw-pin 73 with the depending arm 74 of a bell crank comprising a sleeve 75 which is fulcrumed upon the stud-screw 76 tapped into a lug 77 of the base 1 and having an apertured lateral arm 78 to which is connected an extremity 79 of a spring 80 to whose opposite end is attached the chain 81 extending downwardly therefrom and in practice connected to a knee-lever or treadle beneath the table which supports the machine. Tapped into the rearward extremity of the throat-plate 60 is a stop-screw 82 whose point is adapted to engage the forward extremity of the plate 65 of the angle-lever member to limit the upward movement 100 of the work-retarding lugs 63.

Referring to Fig. 4, the upper surface of the retarding member 63, when in effective relationship with the fabric at the time it is being advanced by the action of the feed-dog, occupies a plane above the upper surface of the latter, which causes the feed-dog to advance the fabric in crowded relationship with the work-retarding member, and directly over the feed-dog the fabric is 120 slightly crowded together to overcome the flattening action of the cloth-presser, which results in the fabric being presented to the action of the needle in its normal condition of elasticity.

It will be readily understood that in practice the operator adjusts the screw 82 to meet the requirements of the body fabric being operated on, the further control of the retarding member being at will to meet 130

the requirements of passing over seams, gussets, bands, etc., dependent upon the nature of the product.

Having thus set forth the nature of the 5 invention, what we claim herein is:—

1. In a sewing machine, the combination with stitch-forming mechanism including a throat-plate and feeding mechanism including a feed-dog, of work-retarding means 10 mounted independently of said feeding mechanism and normally disposed below the upper surface of said throat-plate, and manually controlled means for varying the period of effective action of the work-retarding means during the feed movements 15 of the feed-dog.

2. In a sewing machine, the combination with stitch-forming mechanism including a throat-plate and reciprocating needle, and feeding mechanism including a feed-dog, of a vertically movable work-retarder located back of the line of needle actuation and normally depressed below the upper surface of said throat-plate, and manually controlled means including connections leading 20 downwardly from said work-retarder for varying the period of engagement of the work-retarder with the fabric being acted on during the operation of the feeding 25 mechanism.

3. In a sewing machine, the combination with stitch-forming mechanism including a throat-plate and feeding mechanism including a feed-dog, of a work-retarder normally 30 disposed below the upper surface of said throat-plate and mounted upon a stationary support independently of the feeding mechanism and movable on said support in a direction transverse to the work-advancing 35 movements of the feed-dog, and means including a manually controlled element for varying the period of consecutive engagement of the work-retarder with the fabric being acted on during the operation of the feeding 40 mechanism.

4. In a sewing machine, the combination with stitch forming mechanism, a work-support, and feeding mechanism including a feed-dog, of a work-retarder located at 45 the rear of the line of needle actuation and normally disposed below the upper surface of said work-support and mounted independently of and movable relative to said feeding mechanism, and means including an element adapted for continuous control by the operator for varying the degree of retarding action of said work-retarder with 50 respect to the amplitude of the individual feed movements of said feed-dog.

5. In a sewing machine, the combination with stitch-forming mechanism including a needle, a needle carrying bar and means for actuating the latter, an apertured throat-plate, and feeding mechanism including a feed-dog working through an aperture of 55

said throat-plate, of a work-retarder normally disposed below the upper surface of the throat-plate and pivotally mounted beneath the latter and carrying a work-engaging element adapted to rise through an aperture of said throat-plate for engagement with the work at the rear of said needle and in substantial alinement with said feed-dog, and means for controlling the position of said work-retarder to vary the period of consecutive engagement of the latter with the fabric being acted on.

6. In a sewing machine, the combination with stitch-forming mechanism including a needle, a needle carrying bar and means for actuating the latter, an apertured throat-plate, and feeding mechanism including a feed-dog working through an aperture of said throat-plate, of a work-retarder normally disposed below the upper surface of the throat-plate and pivotally mounted beneath the latter and carrying a work-engaging element adapted to rise through an aperture of said throat-plate for engagement with the work at the rear of said needle and in alinement with said feed-dog, and means including a connection extending below the base of said machine to permit the operator to vary the period and degree of consecutive engagement of the work-retarder with the fabric during the operation of stitching.

7. In a sewing machine, the combination with stitch-forming mechanism, a throat-plate, and feeding mechanism including a feed-dog, of a work-retarder normally disposed below the upper surface of the throat-plate comprising an angle-lever having a lateral arm carrying a work-engaging element working through said throat-plate in substantial alinement with the feed-dog and a depending arm, a fixed fulcrum upon which the angle-lever is mounted, and means including a connection with the depending arm of said angle-lever extending beneath the base of the machine for varying the period and degree of consecutive engagement of the work-retarder with the fabric during the operation of stitching.

8. In a sewing machine, the combination with stitch-forming mechanism, a throat-plate, and feeding mechanism including a feed-dog, of a work-retarder comprising an angle-lever having a lateral arm carrying a work-engaging element working through said throat-plate in substantial alinement with the feed-dog and a depending arm, a fixed fulcrum upon which the angle-lever is mounted, a bellcrank, a connection between the depending arm of said angle-lever and an arm of the bellcrank, and a connection extending downwardly below the base of the machine from a second arm of said bellcrank for controlling the position of said work-retarder.

9. In a sewing machine, the combination with stitch-forming mechanism, an apertured throat-plate, and feeding mechanism including a feed-dog working through an aperture of said throat-plate, of a work-retarder pivotally mounted beneath the throat-plate and carrying a work-engaging element adapted to rise through an aperture of said throat-plate for engagement 10 with the work in alinement with said feed-dog, an adjustable stop for determining the extreme work-engaging position of said work-retarder, and means for controlling the position of said work-retarder.
10. In a sewing machine, the combination with stitch-forming mechanism and fabric-feeding mechanism, the latter comprising a feed-bar with actuating means therefor, and a work-feeding element mounted upon 20 and partaking of all the operative movements of said feed-bar, of fabric retarding means stationary with respect to movements corresponding in direction to the feed of the fabric and normally disposed below the 25 upper surface of the throat-plate to effect at will variations in the extent of the feed movements of the fabric independently of the operative movements of said feeding element.
11. In a sewing machine, the combination with stitch-forming mechanism and fabric-feeding mechanism, the latter comprising a feed-bar with actuating means therefor and the former mechanism including a throat-plate, and a work-feeding element mounted upon 30 and partaking of all the operative movements of said feed-bar, of a work-retarder element stationary with respect to movements corresponding in direction to the feed of the fabric and having its effective surfaces located on opposite sides of the line of seam formation, and operative 35 in a plane above the plane of effective action of said feeding element and normally disposed below the upper surface of the throat-plate to effect at will variations in the extent of the feed movements of the fabric independently of the operative movements of 40 said feeding element.
12. In a sewing machine, the combination with stitch-forming mechanism and fabric-feeding mechanism, the latter comprising a feed-bar with actuating means therefor and the former mechanism including a throat-plate, and a work-feeding element mounted 45

upon and partaking of all the operative movements of said feed-bar, of a work-retarder element stationary with respect to movements corresponding in direction to the feed of the fabric and having its effective surface operative in a plane above the plane of effective action of the feeding element, and normally disposed below the upper surface of the throat-plate to effect at will variations in the extent of the feed movements of the fabric independently of the operative movements of said feeding 60 element.

13. In a sewing machine, the combination with stitch-forming mechanism and fabric-feeding mechanism, the latter comprising a feed-bar with actuating means therefor and the former mechanism including a throat-plate, and a work-feeding element mounted upon 70 and partaking of all the operative movements of said feed-bar, of a work-retarder element stationary with respect to movements corresponding in direction to the feed of the fabric and having its effective surfaces located on opposite sides of the line of seam formation, and operative 75 in a plane above the plane of effective action of said feeding element and normally disposed below the upper surface of the throat-plate to effect at will variations in the extent of the feed movements of the fabric independently of the operative movements of 80 said feeding element.

14. In a sewing machine, the combination with stitch-forming mechanism, feeding mechanism including a feed-dog, and a throat-plate, of work-retarding means 90 mounted independently of and coöperating with said feeding mechanism and normally disposed below the upper surface of the throat-plate, and means continuously under the control of the operator for establishing 95 and interrupting operative relation of said work-retarding means with the fabric being acted on.

In testimony whereof, we have signed our names to this specification, in the presence 100 of two subscribing witnesses.
